UNITED STATES PATENT OFFICE.

HERBERT E. SMITH AND ARTHUR W. SMITH, OF GLOUCESTER, MASSACHUSETTS.

HUMIDIFIER.

Application filed December 28, 1927. Serial No. 243,128.

- This invention relates to a humidifier for use with the heating plants of dwelling houses, buildings and other structures, and particularly with the smoke outlet pipes of said heating plants. The invention has for its object to provide a simple, highly efficient, durable and economical humidifier, which can be quickly and easily assembled and installed.
- 10 The improved humidifier comprises essentially two units, one of which may be designated the humidifier unit and the other the supporting and heating unit.
- 15 The humidifier unit comprises a liquid container and a removable cover therefor, which latter is provided with a liquid inlet for the container and with a valve which is supported by and movable with the said cover and controls said liquid inlet.
- 20 In the preferred form, the fluid inlet valve is automatically operated by a float supported by the cover and movable therewith, and responding to variations in the volume of liquid in the container.
- 25 Provision is made for sealing the cover with a liquid seal, as will be described.
- 30 Provision is made for rendering the apparatus operatively reliable for a long period of time, as will be described.
- 35 The heating unit is constructed so as to be insertible into the smoke outlet pipe of the heater and so that the humidifier unit may be used therewith without materially reducing the area of the smoke outlet pipe. The heating unit may be provided with a cold air check valve, as will be described.
- These and other features of this invention will be pointed out in the claims at the end of this specification.
- 40 Fig. 1 represents the improved humidifier in operative position in the smoke outlet pipe of a heater in a building;
- Fig. 2 is a longitudinal section of the humidifier shown in Fig. 1 on a larger scale;
- 45 Fig. 3, an enlarged detail to illustrate the operation of the float-operated valve;
- Fig. 4, an enlarged detail of the water seal for the cover;
- 50 Fig. 5, a sectional view of the valve construction shown in Fig. 3, and
- Fig. 6, an end elevation of the heating unit shown in Fig. 1.
- 55 Referring to the drawing *a* represents a heater of any suitable or usual construction, which has its smoke outlet pipe *b* connected with the chimney *d* of house or building, represented by the floor *e* thereof.
- The smoke outlet pipe *b* has co-operating with it a humidifier embodying this invention and consisting of a humidifier unit and a heating unit therefor.
- 60 The humidifier unit consists of a vessel or container *10* open at its top and adapted to hold a body *12* of water or other liquid. The container *10* is preferably of sheet metal and is provided with a removable cover *13*, preferably made of sheet metal and having an outwardly extended flange *14* which rests upon the upright side and end walls *15* of the container *10*. The cover *13* is provided with an opening *16* for the passage of liquid into the container and preferably with a separate opening *17* for the passage of vapor out of the container.
- 65 The cover *13* has mounted on it to form part thereof, a valve casing *20* herein shown as substantially conical in shape and having at its upper end a nipple or extension *21* forming a liquid inlet for the valve casing *20* which is designed to be detachably connected by a coupling *22* with a flexible pipe *23*. The valve casing *20* is provided with a bottom member *24* which covers the opening *16* in the cover *13* and is spot welded or otherwise secured to the latter.
- 70 The casing *20* is detachably secured to the bottom member *24* by screws *25* and between the bottom member *24* and the casing is clamped a casting comprising a disk *26* (see Fig. 5) having upright arms *27* spaced apart and connected at their upper ends by a head *28*.
- 75 The cast disk *26* is recessed on its underside to receive a small disk *29* and a larger disk *30*, both of Monel or other rustless metal, and the head *28* is also recessed to receive a small disk *31* of like rustless metal.
- 80 The small disks *29*, *31* form guides for the stem *32* of a valve *33*, both of Monel or like rustless metal, and the larger disk *30* is provided with a port or opening *34* through which liquid passes from the valve casing into the liquid container.
- 85 The port *34* is designed to be automatically closed by the valve *33* and to this end the latter is operatively connected to a float *35*.

within the container. The float lever 35 is pivoted at 36 to the lower end of an arm 37 attached to and depending from the bottom member 24 and extended into the liquid container. Fluid-tight joints are obtained between the cast disk 26 and the valve casing 20 and its bottom member 24 by suitable packing washers 40, 41, (see Fig. 3).

The valve 33 may be connected with the float lever 35 by a pin 42 having conical ends or centering points which enter conical sockets in the lower end of the valve 33 and in the upper surface of a lug 43 on the float lever 35.

15 The lever 35 is suitably connected at one end to a float 44 and is provided at its opposite end with a counterweight 45. The valve 33 is raised to close the port 34 by the float 44, when the desired amount of liquid has been 20 supplied to the container 10, and is opened when the level of the body of liquid has been lowered a given amount.

The float 44 may be confined in a cage or casing 46 attached to the underside of the 25 cover, so that the float may be removed from the container with the cover.

The cover 13 may and preferably will be provided below its top wall 47 with a layer 48 of heat-insulating material of any suitable 30 character, such as cork, felt or the like.

The cover 13 is preferably made as herein shown and is provided with the outer sheet metal plate 47 having side and end walls 49 and an inner sheet metal plate 50 separated 35 from the outer plate 47 by a space which is filled with the insulating material 48.

The inner metal plate 50 is spot welded, riveted or otherwise secured to the side and end walls 49 of the cover, and is preferably 40 provided with depending side and end walls or flanges 52 which project below the bottom of the side and end walls 49 of the cover a material distance and sufficiently to form a sealing member or skirt, which extends below 45 the surface of the body of liquid 12 in the container at all times and co-operates with the side and end walls 15 of the container to form a liquid seal 54 for the joint between the cover and the container, as clearly represented in Figs. 2 and 4, wherein it will be seen that the joint between the outwardly extended flanges 14 on the cover and the outwardly extended flange 55 on the side and end walls 15 of the container is cut off from the 50 vapor space 56 on the container by a column of liquid between the skirt 52 on the cover and the side and end walls 15 of the container.

The liquid seal for the cover avoids the use of gaskets between the cover and the container and the liability of leaks attending their use due to distortion by heat under conditions of use.

The outer and inner sheet metal plates of the cover are connected by copper sleeves or 60 bushings 60, 61 of relatively large diameter

with one of which as 60, the valve casing 20 co-operates, and with the other 61 of which co-operates a vapor outlet 62, preferably made of woven hose having at its lower end a nipple 63 which is inserted into and makes 70 a fluid-tight fit with the sleeve or bushing 61, and is provided at its upper end with a metal disk 64 having an opening co-operating with the hose 62 and covered by a metal plate 65, which is secured to the metal disk by bolts 66 75 or in any other suitable manner and is separated therefrom to leave lateral openings through which vapor is distributed into the room above the floor e.

From the above description, it will be observed that the humidifier unit complete in every respect and comprising the liquid container, the cover therefor provided with the valve casing, with the float for operating the valve and having the vapor outlet pipe 62, can be assembled in the shop and transported as one piece to the place where it is to be installed, and could be applied to the smoke outlet pipe of any heater.

It is, however, preferred to provide a heating unit of special construction, which can be shipped with the humidifier unit and substituted for a section of the smoke outlet pipe at the place of installation. The heating unit preferred consists of a sheet metal body portion 70 and cast end members 71.

Each cast end member 71 is made as a substantially U shaped plate having a substantially straight upper edge 72, a curved bottom 73 and straight sides 74 (see Fig. 6).

The plate or member 71 is provided with a circular opening 740 from which projects outwardly a circular flange 75 and from which extends inwardly a flange 76 of the same shape as the plate and having a groove or channel 77 (see Fig. 2) for the reception of the end of the sheet metal body portion 70, whose end portions are shaped to correspond to the end members 71.

The sheet metal body portion 70 has its 110 ends inserted into the channel or groove 77 in the inner flange 76 and is bolted or otherwise secured to said inner flange.

The body portion 70 is provided with a substantially flat top wall 80 which is provided with an elongated opening 81 having an end and side walls 82, 83 extended above the top wall 80 a substantial distance and preferably a little less than the depth of the liquid container 10, so that when the latter is inserted into the opening 81 in the top wall of the body portion 70, the container will project but a short distance into the body portion, so as to offer a minimum obstruction to the passage of the gases through the body portion and yet project sufficiently to be effectively heated by said gases, and also to facilitate removal of the cover from the container without disconnecting the fluid inlet pipe 23 or the vapor outlet pipe 62.

The sheet metal body portion 70 is also preferably provided with an opening 85 in its curved bottom, with which cooperates a cold air check valve or damper 86 pivoted to a cast frame 87 secured to the sheet metal body portion, and arranged with respect to the opening 85 so that the check damper 86 is arranged to open inwardly into the body portion 70 (see Fig. 2).

- 10 It will be seen that a heater unit of the construction described constitutes a casing in which the humidifier unit is supported and enables the latter and the cold air check to be assembled and shipped to the job as one 15 piece ready to be installed in the smoke outlet pipe of the heater, and requiring only connection of the flexible pipe 23, preferably of copper, with the water pipe 123 of the building and the leading of the vapor outlet pipe 20 62 through the floor *e* of the building, thereby enabling the cost of installation to be reduced to a minimum. The valve casing 20 will preferably have located in it a strainer 91 for the water supplied to the liquid container.
- 25 The valve stem 32 is provided with a removable pin 92 which engages the disk 31 and retains the valve connected with the supporting disk 26, in case the latter is removed from the casing 20.
- 30 The valve 33 and its stem 32 and the guiding disks 29, 31 and the disk 34 forming the valve seat, being of Monel or rustless metal, ensures reliable operation under long periods of use. The disks 29, 30 form a chamber 95 35 into which the water passes from the valve casing 20 through the ports or openings 96 in the disk 26 and from which the water passes through the port 34 into the liquid container 10.
- 40 It will be observed that the liquid seal for the cover enables the cover 13 to be mechanically disconnected from the liquid container, and yet provide a liquid-tight joint between the cover and the container.

45 This is particularly advantageous when the humidifier is used in those localities in which the water contains relatively large amounts of lime and like salts which are deposited readily under heat and form scale or crusts on the liquid container and also on the moving parts of the apparatus.

It is also advantageous in case the liquid container after being installed in service should be burnt out, as might occur in case 55 the water supply valve should be closed and failed to open again. Under such conditions the cover 13 can be lifted from the liquid container and moved to one side sufficiently to permit the liquid container to be removed 60 from the pipe section or heating unit and cleaned or replaced with a new container; the cover at such time being suspended by the flexible pipes 23, 62.

When the liquid container has been replaced in the heating unit, the cover can be

moved back into the container and the humidifier unit restored to its operative condition.

The services of a plumber are not required for this work.

It will also be observed that the valve casing 20 is filled with water in which the valve stem 32 moves and is lubricated by the water which also protects the stem from the heat in the vapor space 56 of the humidifier and thereby prevents the lime and the like being deposited on the valve stem and its guides, which would interfere with the free movement of the valve and render the apparatus less sensitive.

A preferred construction of the invention is herein shown and described but it is not desired to limit the invention to the particular construction shown.

What is claimed is:

1. The combination with a heater unit provided with end openings and with a body portion of greater area in cross section than said end openings and provided with an elongated opening in its top wall, of a humidifier unit 90 having a liquid container forming a closure for said elongated opening and extended but slightly below the top wall of said body portion, and a cover for said liquid container provided with a liquid inlet valve and with a 95 vapor outlet port.

2. A humidifier of the character described comprising a casing open at its ends for connection with a smoke outlet pipe and provided with an intermediate opening in its 100 body portion, a liquid container inserted into said casing through said intermediate opening and forming a closure for the latter, and a cover for said container provided with a liquid inlet valve casing, and with a vapor outlet, a liquid inlet valve carried by the cover for said container, and a float in said liquid container carried by said cover and connected with said inlet valve to operate the same.

3. A humidifier of the character described comprising a casing open at its ends for connection with a smoke outlet pipe and provided with an intermediate opening in its body portion, a liquid container forming a closure member for said intermediate opening, and a 110 cover for said liquid container provided with a liquid inlet valve and with a vapor outlet.

4. A humidifier of the character described comprising a casing open at its ends for connection with a smoke outlet pipe and provided with an intermediate opening in its body portion, a liquid container forming a closure member for said intermediate opening, a cover for said liquid container provided with a liquid inlet valve and with a vapor outlet, and with means extended into the liquid container to co-operate with the walls thereof and form with a portion of the liquid in the container a liquid seal for said cover.

5. The combination with a heater unit com-

- prising substantially U-shaped cast end plates provided with circular openings and with circular flanges, extended outwardly from said openings and having substantially 5 U-shaped flanges extended from the inner faces of said end plates, and a sheet metal body portion substantially U-shaped and having its ends secured to the inner flanges of said end plates and its top wall substantially 10 flat and provided with an elongated opening whose walls extend above said top plate, of a humidifier unit supported by the walls of the opening in said top plate and extended into said body portion but slightly below said 15 top wall.
6. A humidifier of the character described comprising a casing open at its ends for connection with a smoke outlet pipe and provided with an intermediate opening, a liquid container forming a closure for said intermediate opening and supported by said casing, and a cover for said liquid container provided with a sealing member co-operating with the liquid in the container to form a liquid seal for the 20 joint between the cover and said liquid container.
7. The combination with a heater unit provided with end openings and with a body portion provided with an opening intermediate 25 its ends, of a removable closure member for said intermediate opening comprising a humidifier unit provided with a liquid container insertible into and removable from the heater unit through said intermediate opening, a cover for said liquid container, a liquid 30 inlet valve, a float operatively connected with said inlet valve, and a vapor outlet for said liquid container, said liquid inlet valve and float being associated with said liquid container to be moved therewith with relation to 35 said heater unit.
8. The combination with a heater unit provided with an opening, of a removable closure member for said opening comprising a 40 humidifier until provided with a liquid container insertible into and removable from the heater unit through said opening, a cover for said liquid container, a liquid inlet valve, a float operatively connected with said inlet valve, and a vapor outlet for said liquid container, 45 said liquid inlet valve and float being associated with said liquid container to be moved therewith with relation to said heater unit.
9. The combination with a heater unit provided with an opening in its upper surface, a liquid container open at its top and inserted into the opening in said heater unit and provided with a flange overlying and supported by the walls of the said opening, a cover for 50 said liquid container supported thereby and movable therewith and provided with a vapor outlet, and a liquid inlet valve controlling the admission of liquid into said liquid container and movable therewith with relation to said heater unit.
- 55 In testimony whereof, we have signed our names to this specification.
